UNITED STATES PATENT OFFICE

JAMES H. BURDETT, OF HOMEWOOD, ILLINOIS

DESIGN FOR A DISPLAY RACK

Application filed February 15, 1929. Serial No. 30,083. Term of patent 7 years

To all whom it may concern:

Be it known that I, JAMES H. BURDETT, a citizen of the United States, residing at Homewood, in the county of Cook and State of Illinois, have invented a new, original, and ornamental Design for Display Racks, of which the following is a specification, reference being had to the accompanying drawing, forming part thereof.

In the accompanying drawing showing my new design,

Figure 1 is a front view of the rack; and Figure 2 is a plan view of the same. The rectangular figures shown in Figure 1 represent holes or openings through which the goods are displayed.

I claim:

The ornamental design for a display rack as shown and described.

JAMES H. BURDETT.
